[57] CLAIM

The ornamental design for an adjustable platform guide for circular saws, substantially as shown.

DESCRIPTION

FIG. 1 is an isometric view of an adjustable platform guide for circular saws showing my new design;

FIG. 2 is a top plan view thereof;

FIG. 3 is a bottom plan view thereof;

FIG. 4 is a side elevational view taken from the right of FIG. 1;

FIG. 5 is a side elevational view taken from the left of FIG. 1;

FIG. 6 is an end elevational view thereof;

FIG. 7 is an end elevational view opposite that seen in FIG. 6.
